CLAIM

The ornamental desip for a neck light, as shown and described.

DESCRIPTION

FIG. 1 is a first perspective view of a neck light showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a perspective view of an alternate position of the neck light thereof;

FIG. 10 is an enlarged view of the selected portion 10 in FIG. 2; and,

FIG. 11 is an enlarged view of the selected portion 10 in FIG. 7.

The dash-dash broken lines shown in the drawings depict portions of the neck light that form no part of the claimed design. The dot-dash broken lines framing portions of the claimed design are included for the purpose of illustrating enlargements, and form no part of the claimed design.

1 Claim, 11 Drawing Sheets
